(57) **CLAIM**

The ornamental design for an energy storage power supply unit, as shown and described.

DESCRIPTION

1. Energy storage power supply unit
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Perspective
- 1.10 : Enlarged

Fig. 1.1 is a first perspective view of an energy storage power supply unit; fig. 1.2 is a second perspective view thereof; fig. 1.3 is a front view thereof; fig. 1.4 is a rear view thereof; fig. 1.5 is a left side view thereof; fig. 1.6 is a right side view thereof; fig. 1.7 is a top plan view thereof; fig. 1.8 is a bottom plan view thereof; fig. 1.9 is a third perspective

(Continued)

view thereof; and fig. 1.10 is a partially enlarged view of the portion A in fig. 1.9 of the energy storage power supply unit according to our design.
